UNITED STATES PATENT OFFICE

LEWIS FERRY MOODY, OF PHILADELPHIA, PENNSYLVANIA

DOUBLE-RUNNER SPIRAL PUMP

Application filed April 7, 1926. Serial No. 109,207.

This invention relates to hydraulic pumps, and particularly to high-speed propeller type pumps of the double or twin type.

One of the objects of this invention is to provide a pump containing two impellers of opposite hand, to form a pump of high specific speed, high efficiency, and of compact design, in which the flow shall proceed without being subjected to contact with excessive areas of confining walls in the region of the high velocity flow in order to avoid excessive loss of head due to surface resistance, while at the same time the flow shall follow smooth lines without losses due to eddies or disturbances. Another object is to provide a pump of this character which is simple in construction, small in actual dimensions, of light weight, and formed of few parts.

A further object of the invention is to provide a pump of this character with its oppositely directed impellers closely spaced to each other and without unnecessary and objectionable directing surfaces interposed between the impellers to provide forced guidance of the discharge from the impellers into the outward direction.

Further objects and advantages of the invention will be apparent by reference to the following specification and drawings in which

Fig. 1 is a sectional view on line 1—1 of Fig. 2, and

Fig. 2 is a vertical sectional view on line 2—2 of Fig. 1.

In the specific embodiment of the invention illustrated 10 represents a central volute outlet casing, 11 and 12 similar intake casings, and 13 and 14 represent similar axial flow propeller type impellers having unshrouded blades mounted upon a central shaft 15. The intake casings 11 and 12 are each formed with an intake passage 16, 17 leading to the inclined guide vanes 18 and 19. The intake passages may be of the single or double volute form and serve to direct the water from a general radial direction into an axial direction to passages 20—20. From these points the passage walls turn outwardly. The impellers 13 and 14 are keyed or otherwise secured on the shaft 15

and are held against lateral displacement by means of collars 21 and 22 bolted or otherwise secured to the shaft 15. The collars 21 and 22 serve to hold the impeller against a straight central cylindrical spacer in the form of a sleeve 23. Collar 21 may be integral with the shaft and 22 may be a removable collar in halves.

Shaft 15 is supported by bearings 24 and 25 mounted outside of the intake casings 11 and 12, although such bearings could be formed in the walls of the intake casings. The usual stuffing boxes 26 and 27 are provided at the ends of the shaft 15 where it enters the intake casings 11 and 12.

In practice the water entering the passages 16 and 17 is given the desired degree of whirl by entrance vanes 18 and 19, and thence passing through the passages 20—20 is delivered to the impellers 13 and 14 in the form of solid whirling streams, the water from both impellers joining to form a single continuous rotating mass of water. Issuing from the impellers the flow passes outwardly into the outlet 10 and proceeding from the impeller the water is under pressure and will follow natural stream lines to turn without the necessity of any enlarged central core or deflector between them. The whirling flow in leaving the impellers and passing outwardly into the casing 10 will pass from points near the axis to continually greater and greater radial distances from the axis and will be thereby decelerated, according to the principle of constancy of moment of momentum, according to which the linear velocity of rotation of fluid contained within the free space is inversely proportional to its radial distance from the axis.

The casing will, in general, be designed to conform to the velocity determined by this principle and to provide continuous deceleration of velocity as the water flows through the casing. The casing 10 is formed with a throat opening of reduced width between the opposing walls at a point a short distance outside of the impeller tips in order to hold the streams of water together and to avoid any tendency of the natural lines of flow to part from the walls. A casing throat meas-

ured in an axial direction will usually be less than about three-fourths of the impeller diameter in order to conform to the flow. Outside of this throat section where the outward radial components of velocity become sufficiently low, the casing is widened to accommodate the volume of water flowing therethrough.

The casings 10, 11 and 12 may be readily constructed of castings and the entire casing may be easily assembled, as will be seen by an inspection of the drawings. The casings will ordinarily be in two pieces separable on a horizontal plane containing the axis to facilitate removal of the shaft and impellers.

In pumps of the spiral type to which this invention applies the recovery of the energy of the water discharged from the impellers is an important part of the hydraulic action of the pump, since this energy represents a value in high speed pumps of this type which is large compared to the net head against which the pump is delivering.

The entrance guide-vanes 18, 19 are formed to guide the water in a direction of rotation about the impeller axis, this initial rotation for the entering water being in the same sense as the rotation of the impeller. For pumps of special characteristics, the guide-vanes 18, 19 may be omitted, the water then being permitted to take up its natural degree of whirl without forced guidance, the omission of the guide-vanes producing in general a less rapidly falling curve of head relatively to discharge.

The impellers are of high specific speed, having blades which when cut by cylindrical surfaces about the axis are of curved section inclined at relatively small angles to the tangential direction, that is, the direction of motion of the blades. The blades are of relatively small surface area, not materially greater in aggregate surface than the disk area, or net area of the runner passage in a plane normal to the axis; and to avoid undue surface resistance the impeller is free from any shroud ring surrounding the blades. When viewed axially the blades do not overlap each other in the portion near their tips. The impeller will have a small number of blades, usually between three and six. For hydraulic reasons the hubs and sleeve 23 must not be unduly small, but should be of substantial diameter.

The impeller may have blades extending radially outward from the hub, or slightly inclined to the axis when viewed in a section containing the axis as shown in Fig. 1. In the design shown, the discharge from the portion of the blades near the hub is axial or nearly axial, while the discharge from the portion of the blades near the tips has an outward radial component, the turning of the water from axial to radial beginning within the runner. The flows from both runners

near the hubs are allowed to join and turn from axial to radial along their natural lines of flow according to hydrodynamic principles, this turning being produced by an increase in pressure head and corresponding reduction of velocity head where the streams join near the center of the surface of sleeve 23. By omitting any forced guidance of the flow as by an enlarged conical body between the runners, surface friction is minimized, the structure is made compact with the runners close together, and it becomes unnecessary to support a large central deflecting body, either by carrying it on the rotating shaft or by ribs extending from the fixed casing.

While this invention is illustrated and described more particularly with reference to hydraulic pumps having a central discharge passage and separate intake passages it is not confined thereto but is intended to cover hydraulic pumps having a central intake passage and separate discharge passages and any other modifications within the scope of the appended claims.

I claim:

1. A rotary hydraulic pump having in combination two oppositely disposed unshrouded impellers of approximately axial flow type, a casing having a single central passage between said impellers, walls forming the outside boundary of a transition space and having surfaces of revolution smoothly curving from the impeller tips to the casing entrance, and an inside boundary wall of said transition space comprising a sleeve which is continuous in contour with the impeller hubs, and at no point materially greater in diameter than said impeller hubs.

2. A rotary hydraulic pump having in combination two oppositely disposed unshrouded impellers of approximately axial flow type, a single volute discharge casing receiving the discharge from both of said impellers, walls forming the outside boundary of a transition space and having surfaces of revolution smoothly curving from the impeller tips to the casing entrance, and an inside boundary wall of said transition space comprising a sleeve which is continuous in contour with the impeller hubs, and at no point materially greater in diameter than said impeller hubs.

3. A rotary hydraulic pump having in combination two oppositely disposed unshrouded impellers of approximately axial flow type, a single volute discharge casing receiving the discharge from both of said impellers and gradually decelerating the velocity of said discharge, walls forming the outside boundary of a transition space and having surfaces of revolution smoothly curving from the impeller tips to the casing entrance, and an inside boundary wall of said transition space comprising a sleeve which is continuous in contour with the impeller

hubs, and at no point materially greater in diameter than said impeller hubs, the walls of said transition space being adapted to turn the flow from approximately axial to a radial outward direction.

4. A rotary hydraulic pump having in combination two oppositely disposed unshrouded impellers of approximately axial flow type, a single volute discharge casing receiving the discharge from both of said impellers, a common transition space the walls of which turn the discharge from said impellers from approximately axial to a radial direction, the discharge from both of said impellers being permitted to merge freely along a transverse plane midway between said impellers without the interposition of any separating wall or deflecting surface between said impellers.

20 5. A rotary hydraulic pump having in combination two oppositely disposed impellers, a single volute discharge casing receiving the discharge from both of said impellers, and a common transition space, the walls 25 of which turn the discharge from said impellers from approximately axial to a radial direction, the discharge from both of said impellers being permitted to merge freely along a transverse plane midway between 30 said impellers, said impellers being separated by an axial distance substantially less than the outside diameter of either of said impellers.

6. A rotary hydraulic pump having in combination two oppositely disposed unshrouded impellers of approximately axial flow type, a single volute discharge casing receiving the discharge from both of said impellers, and a common transition space, the walls of which turn the discharge from said impellers from approximately axial to a radial direction, the discharge from both of said impellers being permitted to merge freely along a transverse plane midway between 45 said impellers, said impellers being separated by an axial distance less than the outside diameter of either of said impellers.

7. A rotary hydraulic pump having in combination two oppositely disposed unshrouded impellers of approximately axial flow type, a single volute discharge casing receiving the discharge from both of said impellers, and a common transition space, the walls of which turn the discharge from said impellers from approximately axial to a radial direction, the discharge from both of said impellers being permitted to merge freely along a transverse plane midway between said impellers, said impellers being spaced apart at a relatively small distance 55 and surrounded by a wall forming a surface of revolution converging along a smooth curve to a minimum diameter at or near the entrance of the impeller and then continuously curving outward away from the axis

to a radial direction at entrance to the volute casing.

8. A rotary hydraulic pump having in combination two oppositely disposed unshrouded impellers of axial flow type, and a single volute discharge casing receiving the discharge from both of said impellers, said impellers being spaced by a substantially cylindrical sleeve.

9. A rotary hydraulic pump having in combination two oppositely disposed propeller type impellers secured to the same shaft, and a single volute discharge casing receiving the discharges from both of said impellers, said impellers being spaced by a cylindrical sleeve secured to said shaft and rotating with said impellers.

10. In a double pump the combination with a central volute passage, of a cylindrical substantially straight sleeve therein, of a runner on each side thereof, and a plurality of outward passages leading from the runners to the volute passage and discharging therein.

11. In a twin hydraulic pump a central outlet casing and a pair of inlet casings, said inlet and outlet casings being formed with continuous inlet and outlet passages, a pair of impellers in said passages, a shaft upon which said impellers are mounted, and a substantially straight cylindrical sleeve on said shaft spacing the impellers.

12. In a twin hydraulic pump a central outlet casing and a pair of inlet casings, said inlet and outlet casings being formed with continuous inlet and outlet passages, a pair of impellers in said passages, a shaft upon which said impellers are mounted, and a substantially straight cylindrical sleeve attached to said shaft for spacing the impellers and rotating therewith, and guide vanes in the inlets to said impellers.

13. In a double pump a central casing comprising an outer wall, a substantially straight cylindrical sleeve, said wall and sleeve forming between them a volute discharge passage, annular passages discharging axially into said volute, and impellers in said annular passages.

14. A double pump having a central casing formed of an outer wall, a cylindrical sleeve, said wall and sleeve forming between them a volute discharge passage, annular passages communicating therewith, impellers in said annular passages, a shaft extending through said sleeve and carrying said impellers, and an intake passage to each impeller contained between an outer converging surface of revolution and an inner surface of revolution coaxial therewith.

15. In a hydraulic pump the combination with a plurality of unshrouded impellers of substantially axial flow type, of an impeller casing surrounding each of said impellers and a central volute casing, each of said impeller

4
 casings having walls formed as surfaces of revolution smoothly curving from axial to radial direction to form a throat and merging into the walls of the central volute casing and opening through a vane-free passage directly into said central volute casing which flares axially beyond said throat.

16. In a hydraulic pump the combination with a central volute casing of a substantially cylindrical sleeve within said casing, an impeller on each side of said sleeve, guide vanes in advance of each impeller and a plurality of outward passages leading from the impellers to the central volute passage and discharging therein.

17. In a hydraulic pump the combination with a central volute casing, of a substantially cylindrical sleeve within said casing, an unshrouded impeller of substantially axial flow type on each side of said sleeve, fixed guide vanes in advance of each impeller and a plurality of outward passages leading from the impellers to the central volute casing and discharging therein.

18. A rotary hydraulic pump having in combination two oppositely disposed unshrouded impellers of approximately axial flow type, a single volute discharge casing receiving the discharge from both of said impellers, and inner and outer walls forming a common transition space the inner wall extending relatively close and substantially parallel to the axis of the impellers for substantially the entire distance therebetween, said transverse space turning the discharge from said impellers from approximately axial to a radial direction, the discharge from said impellers merging freely between said impellers.

19. A rotary hydraulic pump having in combination two oppositely disposed unshrouded impellers of approximately axial flow type, a single discharge casing receiving a discharge from both of said impellers, walls forming the outside boundary of a free transition space having surfaces of revolution curving from the impeller tips to the casing entrance and an inside boundary wall of said transition space formed by a sleeve continuous in contour with the impeller hubs and smaller in diameter than the diameter of the impellers to permit the flows from the impellers to freely merge between them.

20. In a hydraulic pump the combination with a plurality of unshrouded impellers of substantially axial flow type, of fixed guide vanes in advance of each impeller, an impeller casing surrounding each of said impellers and a central volute casing, each of said impeller casings having walls smoothly curving and merging into the walls of the central volute casing and opening directly into said central volute casing and forming a vane free passage opening directly into said central volute casing.

21. A rotary hydraulic pump having in

combination two oppositely disposed unshrouded impellers of approximately axial flow type, a casing having a single central passage between said impellers, walls forming the outside boundary of a transition space and having surfaces of revolution smoothly curving from the impeller tips to the casing throat, and an inside boundary wall of said transition space comprising a sleeve which is continuous in contour with the impeller hubs and at no point materially greater in diameter than said impeller hubs.

22. In a hydraulic pump the combination with a plurality of impellers of substantially axial flow type, of an impeller casing surrounding each of said impellers and a central volute discharge casing, means for producing two whirling streams axially progressing toward each other, said impellers rotating in the same direction as the streams and acting upon said streams and discharging said streams toward each other, and means whereby the two streams freely merge between said impellers along a transverse plane midway between said impellers including a wall of said rotating element extending between the hubs of the impellers, said wall being everywhere materially smaller in diameter than said impellers whereby a relatively unobstructed axially extending passage is provided between said impellers thereby to effect said free merging.

23. In a hydraulic pump the combination with a plurality of impellers of substantially axial flow type, of an impeller casing surrounding each of said impellers and a central volute casing having a relatively unobstructed axially extending transition space between said impellers, fixed guide vanes in advance of said impellers to impart a whirl to the flow for producing two whirling streams axially progressing toward each other, said impellers rotating in the same direction as the streams and acting upon said streams and discharging said streams toward each other whereby the two streams are efficiently merged between said impellers along a transverse plane midway between said impellers.

24. In a hydraulic pump the combination with a plurality of impellers of substantially axial flow type, of fixed guide vanes in advance of each impeller, an impeller casing surrounding each of said impellers and a central volute casing, each of said impeller casings having walls smoothly curving and merging into the walls of the central volute casing and opening directly into said central volute casing without a central deflecting surface, said walls forming a transition space between the guide vanes and impellers, and a second transition space between the impellers and said central volute casing.

25. A rotary hydraulic pump having in combination two oppositely disposed axially spaced unshrouded impellers of substantial-

ly axial flow type, an impeller casing surrounding each of said impellers and a single central volute casing having a relatively clear axially extending transition space between said impellers, said space having a radial depth extending for a major portion of the distance from the hub to the blade tips, said impellers being of high specific speed and having a relatively small number of 10 blades, not less than 3, the area of which is not materially greater in aggregate surface than the disk area of the passage in the impeller casing in which the impeller is located.

26. In a rotary hydraulic pump having in combination two oppositely disposed unshrouded high speed impellers of substantially axial flow type provided with a relatively small number of blades not less than three, an impeller casing surrounding each 20 impeller, said impellers being spaced apart axially and with a relatively clear transition space therebetween said clear space having a radial depth extending substantially from the hub to the blade tips, and a single central 25 volute casing, said blades having a relatively small surface area non-overlapping in the portion near their tips when viewed axially.

27. A rotary hydraulic pump having in combination two oppositely disposed axially spaced unshrouded high speed impellers of substantially axial flow type, an impeller casing for each impeller and a single central volute casing having a relatively clear axially extending transition space between said impellers, said space having a radial depth extending for a major portion of the distance 30 from the hub to the blade tips, said volute casing also having a throat less than three-fourths of the greatest diameter of the impellers in order to conform to the flow, each of said impeller casings having walls smoothly curving and merging into the walls of the 35 central volute casing.
